United States Patent

Des. 241,318
Patented Sept. 7, 1976

241,318

BOTTLE OR SIMILAR ARTICLE

John Wayne Lewman, Blue Springs, Mo., assignor to Ethyl Development Corporation, Kansas City, Mo.

Filed Apr. 24, 1975, Ser. No. 571,319

Term of patent 14 years

Int. Cl. D9—01

U.S. Cl. D9—113

FIG. 1.

FIG. 2.

FIG. 3.

FIG. 4.

FIG. 1 is a front elevational view of a bottle or similar article embodying my new design;

FIG. 2 is a side elevational view thereof;

FIG. 3 is a top plan view thereof; and

FIG. 4 is a bottom plan view thereof.

I claim:

The ornamental design for a bottle or similar article, substantially as shown.
